[57] CLAIM

The ornamental design for a surgical stapler, as shown and described.

DESCRIPTION

FIG. 1 is a perspective view of a surgical stapler showing our new design;
FIG. 2 is a side elevational view thereof;
FIG. 3 is an elevational view from the side opposite of FIG. 2;
FIG. 4 is a top plan view thereof;
FIG. 5 is a bottom plan view thereof;
FIG. 6 is a front elevational view thereof;
FIG. 7 is a rear elevational view thereof; and
FIG. 8 is a side elevational view showing the surgical stapler partially disassembled.

FIG. 4

FIG. 5
